PORTABLE AMPLIFIER-SPEAKER CABINET

Clarence S. McClellan, Woodland Hills, Calif., assignor
to United Electronics Incorporated, Humacao, Puerto
Rico, a corporation of Delaware

Filed Jan. 4, 1966, Ser. No. 501

Term of patent 7 years

(Cl. D26—14)

Fig. 1

Fig. 3

Fig. 4

Fig. 2

FIGURE 1 is a front, top and right side perspective view of a portable amplifier-speaker cabinet, showing my new design;

FIGURE 2 is a rear, bottom and right side perspective view, to a reduced scale, with the carrying handle in raised position;

FIGURE 3 is a right side elevational view, to a reduced scale, showing the carrying handle in retracted position as in FIGURE 1; and

FIGURE 4 is a left side elevational view to a reduced scale, showing the carrying handle extended as a base support.

The legible matter indicated by broken lines on the top, front and bottom surfaces is for illustrative purposes only.

I claim:

The ornamental design for a portable amplifier-speaker cabinet, as shown and described.
